Inventor:

Winfred K. Reichner.

UNITED STATES PATENT OFFICE.

WINFIELD K. REICHNER, OF PHILADELPHIA, PENNSYLVANIA.

STREET-RAILWAY AUTOMATIC SWITCH-IRON.

No. 885,788.

Specification of Letters Patent.

Patented April 28, 1908.

Application filed December 9, 1905. Serial No. 291,078.

To all whom it may concern:

Be it known that I, WINFIELD K. REICHNER, a citizen of the United States, residing at 1710 Jefferson street, Philadelphia, in the county of Philadelphia and State of Pennsylvania, have invented a new and useful Street-Railway Switch-Point Thrower, of which the following is a specification.

My invention relates to improvements in a switch point throwing device in which a vertical rod is operated in conjunction with a horizontal rod which said horizontal rod is secured to a vertical bracket rigidly supported from the front platform of a car; the object 10 of my improvement is to afford better facilities for street railway switch point throwing. I attain this by a mechanism as illustrated in the accompanying drawing in which A, represents the vertical rod having on its lower 15 end a shoe G, for engaging the switch point, said vertical rod passes through and is loosely held by a guide rigidly secured to the front end of the car. The upper end of said rod A, passes through the end of rod B, and 20 is provided with a thread for receiving a nut by which same is secured thereto. The horizontal rod B, is provided with a hole for receiving the rod A, at one end and at the other 25 end contains a handle I midway between the two ends the rod B, is provided with two pins 30 D, by which same is secured to vertical bracket C, the said rod B, is provided with a notch E, for engaging the catch F, which provides for the holding of rod B, stationary 35 when not in operation. The said catch is provided with pins J, and by that means is secured to the upper end of vertical bracket so as to enable the catch F, to be lifted from or lowered into the notch E, in rod B.

40 The lower end of the vertical bracket is rigidly secured to the front platform of the car, the upper end of the said vertical bracket C,

is cut out so as to permit the insertion of the said rod B, and is also provided with two slots for the reception of pins D, of the rod B, 45 the said slots to be arranged crosswise and admit of an axial movement of the rod B, above the said slots the said rod C, is provided with two holes or pockets for the reception of the pins J, of the catch F.

50 In operation the catch F, is disengaged from the notch E, thus permitting the rod B, controlling the rod A, to lower, as shown in dotted lines, and engage the shoe of rod A, with the switch point and then the rod B, is 55 shifted either right or left which moves the rod A, laterally and by means of the guide H, shifts the switch point.

I am aware that prior to my invention switch point throwers with stationary rigid 60 brackets have been invented, I therefore do not claim such a combination broadly but

I claim:

1. In a switch point throwing device, a vertical rod loosely held by a guide rigidly 65 secured to the front end of a car, a horizontal rod secured by pins D to a vertical bracket rigidly secured upon the front platform of a car, and operatively connected with the aforesaid vertical rod substantially as specified.

2. In a switch point throwing device in which a vertical bracket, secured to a horizontal rod by means of pins D, operates a vertical rod loosely held by a guide rigidly 75 secured to the front end of a car, substantially as specified.

In testimony whereof I have signed my name to this specification in the presence of two witnesses.

WINFIELD K. REICHNER.
